UNITED STATES PATENT OFFICE

93,532

DESIGN FOR A PICTURE CASE

Aurelia Bachman, New York, N. Y.

Application July 13, 1933, Serial No. 48,706

Term of patent 7 years

To all whom it may concern:

Be it known that I, AURELIA BACHMAN, a citizen of the United States, residing at New York city, in the county and State of New York, have invented a new, original, and ornamental Design for a Picture Case, of which the following is a specification, reference being had to the accompanying drawing, forming part thereof.

In the drawing, Fig. 1 shows the front or enclosing face of the two telescoped members which make up the picture case for pocket-book or vest pocket use forming the subject of my invention; and in this view the words "Horn of Plenty" and

"Good Luck Coin" are so arranged as to give symmetry and balance to the representation of the horn; Fig. 2 shows the rear face thereof on which is shown a representation of a barrel of money so full that coins are overflowing to give a circular effect which ties this representation in with the wording around the edge, and Fig. 3 shows a side view.

I claim:

The ornamental design for a picture case, as shown and described.

AURELIA BACHMAN.
